(57) **CLAIM**

I claim a new design for a hasp enclosure, as shown and described.

DESCRIPTION

FIG. 1 is a perspective view of a hasp enclosure according to my new design;

FIG. 2 is a front elevational view of the hasp enclosure of FIG. 1;

FIG. 3 is a top plan view of the hasp enclosure of FIG. 1; FIG. 4 is a left side elevational view of the hasp enclosure of FIG. 1;

FIG. 5 is a right side elevational view of the hasp enclosure of FIG. 1;

FIG. 6 is a rear elevational view of the hasp enclosure of FIG. 1; and,

FIG. 7 is a bottom plan view of the hasp enclosure of FIG. 1.

The phantom lines in FIGS. 1–7 represent environment and are for illustrative purposes only and do not constitute part of the claimed design.
